(57) **CLAIM**

The ornamental design for a crimping tool, as shown and described.

DESCRIPTION

FIG. 1 is a front right perspective view of a crimping tool. FIG. 2 is a right side view of the crimping tool of FIG. 1. FIG. 3 is a left side view of the crimping tool of FIG. 1. FIG. 4 is a front plan view of the crimping tool of FIG. 1. FIG. 5 is a rear plan view of the crimping tool of FIG. 1. FIG. 6 is a top end view of the crimping tool of FIG. 1; and, FIG. 7 is a bottom end view of the crimping tool of FIG. 1. The broken line showing of a crimping tool is for the purpose of illustrating portions of the article and forms no part of the claimed design.

1 Claim, 5 Drawing Sheets
